UNITED STATES PATENT OFFICE.

JACOB B. CHEOUT, OF DES MOINES, IOWA.

ATTACHMENT FOR WAGON-REACHES.

1,093,312.

Specification of Letters Patent. Patented Apr. 14, 1914.

Application filed July 28, 1913. Serial No. 781,668.

To all whom it may concern:

Be it known that I, JACOB B. CHEOUT, a citizen of the United States, residing at Des Moines, in the county of Polk and State of Iowa, have invented a certain new and useful Attachment for Wagon-Reaches, of which the following is a specification.

The object of my invention is to provide an attachment for wagon reaches designed 10 to be mounted on the reach at the point engaged by the hound for reducing friction between the reach and the hound.

More particularly it is my object to provide a casing of simple, durable and inexpensive construction made of a single piece 15 of metal and carrying ball bearings, said casing being peculiarly adapted to be mounted in the reach of a wagon in such a position to present the balls in proper position to be 20 engaged by the hound.

My invention consists in certain details, in the construction, arrangement and combination of the various parts of the device, whereby the objects contemplated are attained, as hereinafter more fully set forth, 25 pointed out in my claims and illustrated in the accompanying drawings, in which:

Figure 1 shows a longitudinal, vertical, sectional view through the running gears of 30 a wagon showing the reach equipped with my improved attachment. Fig. 2 shows a longitudinal, vertical, sectional view through a portion of the reach, and through the casing for containing the ball bearings. Fig. 3 shows a bottom view of a portion of the 35 reach equipped with my improved attachment, and Fig. 4 shows a transverse, vertical, sectional view through the casing above mentioned and one of the balls therein.

In the accompanying drawings, I have 40 used the reference numeral 10 to indicate generally the wheels of the running gears of a wagon, which wheels are mounted on the axles 11. Connecting the front and rear 45 wheels is the reach 12. Extending forwardly from the wagon is a tongue 13. Suitably mounted in the ordinary manner is a hound 14.

My improved attachment comprises a casing, indicated generally in Fig. 3 by the 50 reference character A. The casing A comprises a portion 15 in the form of a hollow race or receptacle. The portion 15 is substantially a three quarter cylinder with an 55 open slot on one side. The width of the opening therein from side to side is less than

the diameter of the cylinder of which the portion 15 forms a part. Formed on the portion 15 at each side of the longitudinal opening therein is a laterally extending 60 flange 16. The flanges 16 are connected at their ends by transverse flanges 17. The flanges 16 are formed with extensions 18 near their ends to receive screws or the like. The flange 17, at one end, is provided with a 65 longitudinally extending tongue 19. The portions 15, 16, 17, 18 and 19 are preferably made of sheet steel so that the tongue 19 may be bent downwardly if desired. The flange 17 on which the tongue 19 is formed is 70 slightly raised to permit steel balls 20 to be inserted into the portion 15 from that end.

My improved attachment is installed on a reach in the following manner: In the under surface of the reach, I cut out a slot 21 of 75 proper size to receive the portion 15, and around the slot 20 is cut out a rabbet to receive the flanges 16 and 17 in the extensions 18 so that when said attachment is installed the flanges are flush with the under surface 80 of the reach. The rearward flange 17 on which the tongue 19 is formed is preferably so located that it is never engaged by the hound 14. The slot or notch 21 is somewhat longer than the member 15 to permit the removal of the balls 20. The attachment is secured to the reach by means of screws or the like 22 mounted in the extensions 18 and screwed into the reach. The tongue 19 may be bent over, as shown in Fig. 2, for holding 85 the balls in the portion 15, or a bolt may be extended through the tongue 19 or the raised portion of the flange 17 and into the reach. If it is desired to remove any of the balls for replacing them, the tongue 19 may be 90 straightened out and the balls removed and replaced.

The advantages of my improved attachment may be largely seen from the foregoing description. It is well known by 100 teamsters that the wear of the hound on the reach is very great and in heavy hauling it is frequently necessary to repair or replace the reach. This is true even when the protecting irons are used. When my improved 105 attachment is installed on the reach the friction between the reach and the hound is entirely done away with. The hound frictionally engages the balls 20 and the wear on the hound is greatly reduced. The use of the 110 balls thereby lightens materially the work of the team in turning the wagon. It will

therefore be seen that my improved attachment reduces the work of the team and also the wear on the parts so that the attachment pays for itself within a short time.

5 It will be understood that some changes may be made in the construction of my device without departing from its essential features, and it is my purpose to cover by this application any such changes which 10 may be included within the scope of the appended claims.

I claim as my invention:

1. An attachment for vehicle reaches, comprising a receptacle substantially in the 15 shape of a three quarter cylinder having a longitudinal slot in its lower portion, said three quarter cylinder being provided at the sides of said slot with laterally extending flanges and with transverse flanges connecting 20 said side flanges, the flange at one end being slightly bent outwardly at its center to permit the insertion of balls into the three quarter cylinder and being provided with a tongue capable of being bent to proper position 25 for holding the balls in position.

2. In a device of the class described, the combination of a wagon reach having a longitudinal slot in its lower surface, with a receptacle having substantially the form of a three quarter cylinder provided with laterally extending flanges at the edges of the longitudinal openings in said three quarter cylinder and with transverse flanges connecting said side flanges one of said transverse flanges being bent away from the body 30 of said three quarter cylinder to permit the insertion of balls into the latter, said last named flange having a tongue formed thereon and designed to be bent inwardly for holding balls in said three quarter cylinder, 40 and a plurality of balls in said three quarter cylinder, said attachment being received in said slot in said reach, and said flanges being secured to the reach.

Des Moines, Iowa, July 18, 1913.

JACOB B. CHEOUT.
